UNITED STATES PATENT OFFICE.

JAMES H. BAKER, OF ALLEGHENY, PENNSYLVANIA.

DESIGN FOR AN ANGLE-IRON.

SPECIFICATION forming part of Design No. 28,865, dated June 14, 1898.

Application filed October 30, 1897. Serial No. 656,969. Term of patent 14 years.

To all whom it may concern:

Be it known that I, JAMES H. BAKER, a citizen of the United States, residing at Allegheny, in the county of Allegheny and State of Pennsylvania, have invented and produced a new and original Design for an Angle-Iron, of which the following is a specification.

In the accompanying drawing, which makes part of this specification, the figure is an isometrical perspective of the angle-iron.

The design consists of a peculiar right-angled shape, hereinafter described. This shape has two members A and B. Member A is longitudinally and convexly curved upon its upper surface at a . Member A unites with mem-

ber B upon a curve c of substantially the same radius as the curve which forms the surface a .

The corners b' and b'' of the member B are rounded. The opposite lower corner is rounded, as seen at a' .

Having described my invention, I claim—

The design for an angle-iron, substantially as shown and described.

In testimony whereof I have hereunto set my hand this 22d day of October, A. D. 1897. 25

JAMES H. BAKER.
